CLAIM

The ornamental design for aquarium gang valve, as shown and described.

DESCRIPTION

FIG. 1 is a perspective view taken from the top, front and left side of an aquarium gang valve showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof, the right side being a mirror image of the left side shown;

FIG. 7 is a cross sectional view taken along the line VII—VII of FIG. 2;

FIG. 8 is a cross sectional view taken on line VIII—VIII of FIG. 2; and

FIG. 9 is a cross sectional view taken on line IX—IX of FIG. 6.

The fragmentary broken line representation of an aquarium in FIG. 1 is for purposes of illustration only and forms no part of the claimed design.
